UNITED STATES PATENT OFFICE

2,610,594

COMBUSTION CHAMBER FOR DOMESTIC OIL BURNERS AND THE LIKE

John N. Hauck, Red Hill, Pa., assignor to Columbia Boiler Company, Pottstown, Pa., a partnership

Application January 19, 1951, Serial No. 206,857

1. Claim. (CL 110—86)

1

This invention relates to combustion chambers for domestic oil burners and the like and more particularly to improved combustion chambers and provisions for air supply thereto.

It is the principal object of the present invention to provide an improved combustion chamber for domestic oil burners, in which an improved combustion chamber of unit type is provided for assembly in the boilers, the combustion chamber being provided of great strength, with side walls exteriorly formed to provide insulating air spaces, with improved joints between the sections thereof, and with provisions for the introduction of air to minimize noise and pulsations.

It is a further object of the present invention to provide an improved oil burner flange for use with combustion chambers of the character aforesaid.

Other objects and advantageous features of the invention will be apparent from the specification and claim.

The nature and characteristic features of the invention will be more readily understood from the following description, taken in connection with the accompanying drawings forming part hereof, in which:

Figure 1 is a vertical central section view taken from front to rear of the lower portion of a domestic heating boiler having a combustion chamber and flange in accordance with the present invention;

Fig. 2 is a horizontal sectional view taken approximately on the line 2—2 of Fig. 1;

Fig. 3 is a view in perspective of the flange removed from the front wall of the boiler; and

Fig. 4 is a perspective view of the combustion chamber removed from the boiler.

It should, of course, be understood that the description and drawings herein are illustrative merely and that various modifications and changes can be made in the structure disclosed without departing from the spirit of the invention.

Like numerals refer to like parts throughout the several views.

Referring now more particularly to the drawings, a domestic heating boiler is shown generally at 10, with side walls 11 and 12, front and rear walls 13 and 14 extending between the side walls 11 and 12, and a bottom wall or floor 15 connected to the side walls 11 and 12 and to the rear wall 14. The walls are preferably of metal and connected at their meeting edges by welding. A removable lower front wall plate 16 is also provided, held in position by studs 9, and has an opening 29 therethrough.

2

In the space above the bottom wall 15, between the front wall plate 16 and the rear wall 14, and between the side walls 11 and 12, a combustion chamber 17 of refractory material is provided.

5 The combustion chamber 17 is preferably made in two parts, constituting front and rear sections 18 and 19, for ease of moulding.

The rear section 19 preferably has an upper flat face 20 with an inclined edge 21 extending

10 downwardly therefrom, and has an integral rear wall 22, bottom wall 23 and side walls 24 and 25.

In the portions of the rear section 18 at the exterior corners provided by the junction of the side walls 24 and 25 with the rear wall 22 the material extends outwardly so as to be alined with the rear wall 14 and side walls 11 and 12 to provide a strong corner construction. The rear wall 22, between the ends, has a portion removed during casting to provide an air space 26 in front of

20 the rear wall 14. Along the side walls 24 and 25 part of the material is also removed during the casting to provide side air spaces 27 and 28.

At the front edge of the rear section 19, a V-shaped bead or tongue 30 is provided, extending 25 downwardly along the front faces of the side walls 24 and 25 and the front face of the bottom wall 23 for engagement in a complementary groove 31 formed in the rear faces of the front section 18.

The front section 18 has side walls 32 and 33 corresponding to and alined with the side walls 24 and 25, and a bottom wall 34 corresponding to and alined with the bottom wall 23. The side walls 32 and 33 have exterior portions thereof removed during casting to provide side air spaces 35 and 36 respectively alined with the air spaces 27 and 28.

The bottom walls 23 and 34 also have exterior portions removed during casting to provide bottom air spaces 37 and 38.

40 The front section 18 has a front wall 40 which at its junction with the side walls 32 and 33 has the exterior corners thereof with portions extending into contact with the side walls 11 and 12 and the front plate 16.

45 The front section 18 has an exterior central front wall panel 41 which may be offset rearwardly from the front plate 16 for purposes to be explained. The front wall 40 may be relieved, during casting, at the sides of and below the front wall panel 41 to provide front side and front lower air spaces 42 and 43.

The front wall 40 at the panel 41 is provided with an opening 44 extending from the front to the rear thereof for the reception of a burner nozzle or blast tube 45, which may be cemented in place, and at a plurality of locations concentric

therewith has openings 46 extending therethrough for the delivery of air around the stream from the blast tube 45. The rear offsetting of the panel 41 permits of access of air to the openings 46.

The front plate 16, in order to provide proper support for the alinement of the blast tube 45 is preferably provided with a flange 50 having a hollow cylindrical portion 51 for engagement with or securing to the blast tube 45 and a radially extending portion 52 which is adapted to be clamped, by bolts 53 extending through bolt holes 54, to the front plate 16. On the rear face of the radially extending portion 52 of the flange 50, a plurality of radial slots 55 are provided for access of air to the opening 29 in the plate 16 and therefrom to the openings 46.

The mode of use, will it is thought, be apparent from the foregoing but it may be noted that with an oil burner in operation, flame and the mixture of burning fuel and air from the blast tube 45 enters the combustion chamber 17 substantially horizontally and then passes upwardly for heat exchange with the heat transfer surfaces (not shown) of the boiler 10, disposed thereabove. As the burning continues, air is inspirated through the slots 55, past the edge of the opening 29 and through the openings 46 into the combustion chamber 17 around the flame and burning combustible material from the blast tube 45.

The introduction of air in this manner has been found to stabilize the combustion, to reduce the tendency to pulsations observed with various types of burners now employed, and to reduce the noise attendant upon the combustion with burners now available.

The exterior air spaces around the combustion chamber increase its life, reduce its weight and reduce the heating of the exterior walls.

I claim:

In a boiler having a plurality of vertical side walls, a combustion chamber casing of refractory material at the lower portion of said walls, said combustion chamber casing being open at the top for delivery of combustion gases to the

boiler and having a front wall with an opening therethrough for the reception of a burner, a front wall plate exteriorly disposed with respect to the front wall of said combustion chamber casing and having an opening therethrough for the burner, the interior diameter of said casing opening being greater than the exterior diameter of said burner to provide an air passageway, the front wall of said combustion chamber casing having portions thereof spaced from said front wall plate to provide an air passageway in communication with said first mentioned air passageway, a burner supporting member having a cylindrical portion for supporting engagement with the burner and having a flange portion extending outwardly from said cylindrical portion and secured to said front wall plate, said flange portion having an inner face in engagement with said front wall plate, said inner face having a plurality of grooves extending outwardly to provide air passageways in communication with said first mentioned passageway and said front wall of said combustion chamber casing having a plurality of openings therethrough in communication with the interior of said combustion chamber casing in spaced relation to said burner opening and in communication with said second mentioned passageway.

JOHN N. HAUCK.
